UNITED STATES PATENT OFFICE.

JOHN McWILLIAMS, OF NEW LEBANON, NEW YORK.

CAN-OPENER.

SPECIFICATION forming part of Letters Patent No. 280,495, dated July 3, 1883.

Application filed May 16, 1883. (Model.)

To all whom it may concern:

Be it known that I, JOHN McWILLIAMS, of New Lebanon, in the county of Columbia and State of New York, have invented a new and 5 Improved Can-Opener, of which the following is a full, clear, and exact description.

The object of my invention is to provide a new and improved can-opener which can cut on a straight or curved line.

10 The invention consists in a can-opener formed of two levers pivoted to each other, of which levers one is provided with a blade at its lower end, and the other has a plate pivoted to its lower end, which plate is provided 15 with a flange adapted to rest upon the surface being cut, the plate thus serving as a guide and traveling fulcrum for the cutting-blade.

Reference is to be had to the accompanying drawings, forming part of this specification, in 20 which similar letters of reference indicate corresponding parts in all the figures.

Figure 1 is a longitudinal elevation of my improved can-opener. Fig. 2 is a longitudinal elevation of the same, showing it inclined. 25 Fig. 3 is an edge elevation of the lower part of the same. Fig. 4 is a longitudinal elevation of the inner side of the blade. Fig. 5 is a perspective view of the pivoted guide. .

Two levers, A, provided at the upper ends 30 with handle-loops B, are pivoted to each other by a pivot, A', in the same manner as the blades of a pair of scissors are pivoted, and to the inner surface of one lever a pointed blade, C, is riveted, which blade can be made 35 integral with the lever, instead of being riveted thereto. The other lever A is provided with a recess, D, in the inner side or surface, at the lower end, and to the lower end of the said lever a plate, E, is pivoted, of the same thickness as the depth of the recess D, which plate is provided at its lower edge with an outwardly-projecting flange, F, which is at right angles to the plate, the plate and flange forming a right-angled sharp edge. One end of the 40 flange F projects beyond the end of the plate, 45

as shown. When the can-opener is not in use, the flange is folded against the edge of the lever, the plate E filling the recess D, and the surface of the plate E being flush with the inner side of the lever, so as not to interfere with 50 the operating of the device. The lower edge of the plate E is to rest closely against the adjoining surface of the blade C, as shown in Fig. 3.

The operation is as follows: The plate E is 55 swung down, so that it will be about at right angles to the lever to which it is pivoted, and the point of the blade C is forced through the can-cover until the flange rests upon the said cover. If the upper ends of the levers are 60 forced down in the direction of the arrow a', the blade C will be swung upward in the direction of the arrow b' and will cut through the cover. The levers are then moved in the inverse direction of the arrow a' and moved 65 forward, and are then again pressed down in the direction of the arrow a', and so on. If desired, the levers can be operated in the same manner as the blades of a pair of scissors, the blade C cutting when the upper ends of the 70 levers are pressed together, and the plate E being moved forward when the upper ends of the levers are separated. The blade C cuts against the right-angled edge of the flanged plate E. The flanged plate forms a guide and 75 a movable fulcrum for the cutting-blade.

Having thus described my invention, what I claim as new, and desire to secure by Letters Patent, is—

A can-opener consisting of two cross-pivoted levers carrying, respectively, the blade C and plate E, the latter being pivoted in a recess, D, and provided with a right-angled sharp-edged flange, F, projecting beyond it, as shown and described. 80

JOHN McWILLIAMS.
